UNITED STATES PATENT OFFICE.

FRIEDRICH BOHNE, OF LAUENSTEIN, GERMANY.

MEANS FOR LOCKING FOLDING DOORS OR THE LIKE.

SPECIFICATION forming part of Letters Patent No. 788,626, dated May 2, 1905.

Application filed May 18, 1904. Serial No. 208,587.

To all whom it may concern:

Be it known that I, FRIEDRICH BOHNE, cabinet-maker, a subject of the King of Prussia, Emperor of Germany, and a resident of Lauenstein, in the Empire of Germany, have invented new and useful Means for Locking Folding Doors or the Like, of which the following is a specification.

The present invention relates to improved means for automatically locking folding doors and windows in such a manner that the closed side or wing is secured in its position without the necessity of a push-bolt to be actuated by hand, as heretofore.

Further objects of my invention are to simplify and cheapen the construction and to render more efficient, serviceable, and durable in operation devices of the kind referred to.

With these ends in view the invention consists in the novel combination, arrangement, and adaptation of parts, all as more fully hereinafter described, shown in the accompanying drawings, and then specifically set out in the appended claim.

In the drawings, Figure 1 shows a front elevation of a folding door, partly in section, to illustrate the interior mechanism of the locking appliance. Fig. 2 is a vertical section on line A B of Fig. 1. Fig. 3 is a vertical section on line C D of Fig. 1.

The two sides or wings of the door or window are turnable in hinges of the frame *a*, as usual. Said frame *a* shows in a recess at the meeting points of the two wings a bolt *c*, pivoted around a horizontal pin *b*. This bolt *c*, in the shape of a two-armed lever, is pressed downwardly by means of a spring *d*, so that the two bolt-heads *e*, *f* project into the path of the two sides or wings of the door or window. Both bolt-heads are rounded or tapered, as shown in Figs. 2 and 3. The bigger head *e* serves for locking the left-hand side or wing in its closed position when the right-hand side or wing is opened. Pulling on the left-hand

wing causes the bolt-head *e* to be pressed backwardly, whereupon this wing can also be opened. The left-hand wing shows on the upper surface of its top transverse bar a recess surrounded by a metal plate *g* for the reception of the bolt-head *e*. In order to lock both sides or wings in the frame *a* when closing them, so that they are insured against

rattling, the right-hand side or wing when swung home presses with a metal plate *h* on the upper surface of its top transverse bar 55 against the smaller bolt-head *f*, thereby turning the bolt *c* around its fulcrum *b*, so that the bolt-head *e* is further pushed into the left-hand wing. The aperture of the plate *g* being chosen of a size to firmly hold the bolt-head *e* when fully depressed, rattling of the door or window will be completely obviated.

The hereinbefore described locking arrangement can be adapted to doors and windows of various dimensions. 65

I am aware that previous to my application lever-catches for double doors were employed. In consequence I do not extend my claim to a lever-catch *per se*, but to the combination of a beveled or tapered head at each 70 end of the lever, said heads, of different size, projecting into the path of the two doors or wings and the smaller head adapted to wedge the larger head into the metal-lined recess on top of the respective door or wing when the 75 second door or wing is being closed.

What I do claim as my invention, and desire to secure by Letters Patent, is—

Improved means for automatically locking folding doors and windows, comprising a 80 spring-influenced bolt *c* in the shape of a two-armed lever rotatable around a horizontal pivot *b*, a head at each end of the bolt *c* projecting into the path of the two sides or wings of the door or window, both heads *e*, *f* being 85 tapered to allow the closing and opening of the doors by pushing and pulling; a metal-lined recess in the upper surface of the top transverse bar of one of the wings for the reception of the larger bolt-head *e*, and a metal 90 plate *h* on the upper surface of the top transverse bar of the second wing, said metal plate *h* adapted to press back the second bolt-head *f* and to firmly wedge the bolt-head *e* in its metal-lined recess, substantially as described 95 and shown and for the purpose set forth.

In witness whereof I have hereunto signed my name, this 28th day of April, 1904, in the presence of two subscribing witnesses.

FRIEDRICH BOHNE.
